COMBINED DISPLAY AND DISPENSING STAND

Lester S. Johns, 12881 Charloma Drive, Tustin, Calif.

Filed May 11, 1964, Ser. No. 79,903

Term of patent 14 years

(Cl. D80—9)

FIG. 1

FIG. 2

FIG. 3

FIG. 4

FIG. 5

FIG. 6

FIG. 7

FIG. 1 is an exploded perspective view of a combined display and dispensing stand embodying my new design;

FIG. 2 is an exploded rear elevational view thereof;

FIG. 3 is a top plan view of the bottom unit thereof;

FIG. 4 is a top plan view of the top unit thereof with the cover removed;

FIG. 5 is a perspective view of a modified form of the combined display and dispensing stand shown in FIG. 1 through 4;

FIG. 6 is the front elevational view of the stand shown in FIG. 5; and

FIG. 7 is a side elevational view of the stand shown in FIG. 5.

I claim:

The ornamental design for a combined display and dispensing stand as shown and described.
